FIG. 1.

UNITED STATES PATENT OFFICE.

WILLIAM F. FOCHA, OF RICHMOND, CALIFORNIA, ASSIGNOR OF ONE-HALF TO PATRICK
W. McDONOUGH, OF RICHMOND, CALIFORNIA.

BOTTLE-SAFE.

1,217,430.

Specification of Letters Patent. Patented Feb. 27, 1917.

Application filed September 14, 1916. Serial No. 120,126.

To all whom it may concern:

Be it known that I, WILLIAM F. FOCHA, a citizen of the United States, residing at Richmond, in the county of Contra Costa 5 and State of California, have invented certain new and useful Improvements in Bottle-Safes, of which the following is a specification.

This invention relates to bottle safes, and 10 more particularly to a safe for milk bottles and the like.

One of the main objects of the invention is to provide a safe for holding milk bottles so constructed as to prevent removal of a 15 bottle from the safe without the insertion of a second bottle.

A further object is to provide a safe of simple construction and operation provided with means for directing the bottles into 20 proper position to operate the locking mechanism of the same, such means being also adapted to prevent tampering with the interior of the safe.

Further objects will appear from the 25 tail description.

In the drawings:

Figure 1 is a front perspective view of the safe,

Fig. 2 is a transverse vertical sectional 30 view taken near one end of the safe,

Fig. 3 is a longitudinal vertical central 35 sectional view, and

Fig. 4 is a horizontal sectional view near the top of the safe.

The base plate 1 is provided with an integral peripheral flange 2 to which is secured the box-like cover 3. The cover and the base are both stamped out of sheet metal, and the cover is provided, at its back 40 corners, with horizontally extending tabs or ears 4 which are perforated to receive securing screws 5 for the purpose of securing the safe to the wall of a house, or any other suitable anchoring means.

The base 1 is provided, near each end, with a circular opening 6. These openings are of a size to receive the upper end of a milk bottle 7 of usual construction. A plate 8 is mounted on the base 1, between the 45 openings 6, and is slidable in flanged U-guides 9 secured to the base plate at each side thereof. The plate 8 is of a length slightly greater than the distance between the two 50 openings 6 and is provided, near each end,

with an arcuate recess 8^a which is curved on 55 an arc of the same radius as the openings.

A bracket plate 10 is riveted to the base plate 1, near each end thereof. Each bracket plate is recessed to fit about the outer half of each of the openings 6 and is turned up 60 at right-angles, at each end, to provide a vertical arm standard 11. The arms 11 of each bracket plate are positioned at each side of the opening 6, at the center thereof and are diametrically opposite. A rectangular 65 latch 12 is pivotally secured at its upper end to the upper end of the standard 11. The body 12^a of this latch is of approximately elliptical shape and, when the latch is in operative position, extends inward 70 above the opening 6.

The two latches at each side of the safe are in horizontal alinement and are connected by a resilient spring wire rod 13, the ends of which are loosely secured in the latches 75 near their lower ends. These two rods are connected by a transverse tension rod 14, the ends of which are hooked about the rods 13 at their longitudinal centers. The rod 14 is of such length as to constantly force the two 80 rods 13 toward each other so as to maintain them under tension. This construction of the rods 13 forms spring members which constantly tend to force the latches 12 toward each other.

Each of the latches 12 is provided, at its lower end, with an inwardly projecting horizontal arm 15. This arm is provided, at its inner end, with a rectangular recess 16 and a contiguous inwardly beveled portion 17. 90 When the locking plate 8 is in either one of its outermost positions longitudinally of the safe, it projects over one of the openings 6 at its outermost end, the recess at its other end coinciding with the other opening 6 so 95 as to leave the same unobstructed.

In Fig. 4 of the drawings, the plate 8 is shown as being moved into its extreme position toward the right-hand end of the safe. In this position it projects over the right-hand opening 6, the left-hand opening being left unobstructed by the plate. With the plate in this position, the two latches 12 at the left-hand end of the safe are forced inward so as to bring the notches 16 thereof 100 into position to receive the left-hand corners of the plate. Also the vertical lateral walls or flanges of the plate 8 will engage the

body portions of the latches at the right hand end of the casing, as will be clear from Figs. 2 and 3 of the drawings. By this means movement of the plate when in operative position, in either direction is positively prevented.

- If a bottle is inserted into the safe and the plate 8 is moved so as to project over the opening 6 through which the bottle is inserted, the bottle will be secured in the safe.
- 10 In order to remove the bottle it is necessary to insert a second bottle into the other opening of the safe. When this is done, the second bottle will engage the projecting bodies 12^a of the latches 12 so as to move the arms 15 thereof outward and release the locking plate so as to permit movement of the same toward the second bottle which has been inserted. By withdrawing the first bottle from the safe, the locking plate will be forced toward the second bottle so as to pass beneath the peripheral bead or shoulder at the upper end thereof and, when in its outermost position, will be engaged by the other latches 12 so as to be locked against movement. This operation will be clear upon reference to Figs. 3 and 4 of the drawings. Assuming that a bottle of milk, indicated by the numeral 7 in Fig. 3, is locked 25 in position in the right-hand opening 2 of the safe, the plate 8 is held against movement by the latches 12 at the left-hand end. To remove the bottle of milk an empty bottle is inserted through the opening at the left-hand end of the safe, the shoulder or bead at the upper end of this empty bottle will engage the body 12^a of the latches 12 which project or extend beyond the opening and will force the latches outward so as to 30 move the arms 15 thereof out of engagement with the plate 8. With the latches at the left-hand end of the safe in this position, if the bottle be withdrawn from the right-hand end or compartment of the same, the bead 35 thereof will engage the recess 8^a of the plate, so as to force the same into its extreme position toward the left-hand end of the casing. When the locking plate reaches this position, the latches 12 at the right-hand 40 end of the casing will be forced inward by the spring rods 13 so as to engage the right-hand end of the plate and secure the empty bottle in the safe. From this it will be evident that a bottle which has once been secured 45 in the safe can only be released by inserting a second bottle. By this means I prevent theft of the bottled milk which is placed in the safe and also, as it is necessary to insert a second bottle into the safe in order to release the bottle containing the milk, I insure 50 that the milk dealer will receive an empty bottle for every bottle which he leaves containing milk.

Bracing bars 18 are secured to the standards 65 11 and serve to hold the same in proper

spaced relation. These bars effectually prevent bending of the standards due to the pressure exerted by the spring rods 13, and are positioned a sufficient distance above the openings 6 to prevent all interference with the insertion or withdrawal of bottles into or from the safe. 70

In order to facilitate the insertion of bottles into the safe, I provide, below each opening 6, a downwardly extending funnel 75 19. This funnel is provided at its upper end with a peripheral flange 20 which is secured to the base plate 1. These funnels, in addition to facilitating the insertion of a bottle into the safe, also render it impossible to obtain access to the interior of the safe so as to release the locking plate 8 without inserting a bottle into the opening. 80

There may be changes made in the construction and arrangement of the different 85 parts of my invention without departing from the field and scope of the same, and I intend to include all such changes, as fall within the scope of the appended claims in this application in which a preferred form 90 only of the invention is disclosed.

What I claim is:

1. The combination of a casing having spaced openings, a plate slidably in the casing and adapted when in operative position 95 to extend beyond the edge of one of said openings, and means for locking the plate in operative position, said locking means being releasable only by the insertion of a bottle through the other opening. 100

2. The combination of a casing having a pair of spaced openings through its bottom, a plate slidably mounted in the casing between the openings of greater length than the distance between the openings, said plate 105 having limited movement in either direction longitudinally of the casing and having each end recessed to correspond to the inner portion of the adjacent opening, and means carried by the casing and engaging with the 110 plate for locking the plate against movement.

3. The combination of a casing having a pair of spaced openings through its bottom, 115 a plate slidably mounted in the casing between the openings, and pivotally mounted latches adapted to engage the ends of the plate so as to lock it in operative position extending beyond the edge of one of said openings, said latches being so positioned as 120 to be moved into inoperative position so as to release the plate when a bottle is inserted through one of the openings.

4. The combination of a base plate having two central openings, a cover secured on the base plate, a locking plate slidable on the base plate between the openings of greater length than the distance apart of the openings and provided in each end with an arcuate recess struck on an arc of the same 125 130

radius as the radius of the openings, and spring-pressed latch members mounted on the base plate at each end of the locking plate and adapted to engage the ends thereof so as to prevent movement of the locking plate, when said plate is moved into its extreme position in either direction, said latch members extending above the openings when in locking engagement with the locking plate.

5. The combination of a base plate having two circular openings, a cover secured on the base plate, a locking plate slideable on the base plate between the openings of greater length than the distance apart of the openings and provided at each end with an arcuate recess, a pair of diametrically opposite latches adjacent each opening, the two pairs of latches coöperating to engage the ends of the locking plate so as to prevent movement thereof when the plate is moved into its extreme position in either direction with the latches at one end of the plate extending beyond the adjacent opening, and 10 means for forcing the latches of each of said pairs of latches toward each other.

6. The combination of a base plate having two circular openings, a cover secured on the base plate, a locking plate slideable on the base plate between said openings, a pair of rectangular latches mounted adjacent each opening and positioned diametrically opposite each other, the pairs of latches coöperating to engage the ends of the locking 15 plate so as to prevent movement thereof when the plate is moved into its extreme position in either direction, resilient rods ex-

tending longitudinally of the casing and loosely connected at their ends to the longitudinally alined pairs of latches, and a transverse tension rod loosely connected to the longitudinally extending rods intermediate their ends and exerting tension on the same.

7. The combination of a base plate having two circular openings, a cover secured on the base plate, a locking plate slideable on the base plate, between said openings, a pair of rectangular latches mounted adjacent each opening and positioned diametrically opposite each other, the two pairs of latches coöperating to engage the ends of the locking plate so as to prevent movement thereof when the plate is moved into its extreme position in either direction, resilient rods 45 extending longitudinally of the casing and loosely connected at their ends to the longitudinally alined openings of the pairs of latches, a transverse tension rod loosely connected to the longitudinally extending rods 50 intermediate their ends and exerting tension on the same, and funnels secured to the base plate and communicating with the openings therethrough, said funnels being adapted to facilitate the insertion of bottles into the casing and to prevent access to the interior of 55 the casing.

In testimony whereof I affix my signature in presence of two witnesses.

WILLIAM F. FOCHA.
